HOSPITAL EMERGENCY CART OR THE LIKE

Harry N. Ceranowicz, Webster, and Warren P. Ganter,
Rochester, N.Y., assignors to Nunn Ceranowicz and Associates, Inc., Rochester, N.Y.

Filed Apr. 11, 1973, Ser. No. 350,039

Term of patent 14 years

Int. Cl. D12—02

U.S. Cl. D12—28

FIG. 1

FIG. 3

FIG. 1 is a front perspective view of a hospital emergency cart showing the front and one side of our design wherein two doors are shown in an open position;

FIG. 2 is another front perspective view of the hospital emergency cart that is shown in FIG. 1 wherein two doors are shown in a closed position; and

FIG. 3 is a perspective view as seen from the rear of FIG. 2.

We claim:

The ornamental design for a hospital emergency cart or the like, as shown.
